CLAIM

The ornamental design for a housing for a combination tool, as shown.

DESCRIPTION

FIG. 1 is a top plan view of a housing for a combination manicure tool, showing my new design;

FIG. 2 is a front elevational view thereof;

FIG. 3 is a bottom plan view thereof;

FIG. 4 is a front elevational view thereof, showing proposed tool in open position;

FIG. 5 is a right side elevational view thereof, the left side being a mirror image; and

FIG. 6 is a perspective view thereof.

FIG. 1

FIG. 2

FIG. 3

FIG. 4

FIG. 5
